METHOD OF STORING AND BURNING COMBUSTIBLE MIXTURES

Filed Nov. 13, 1933

UNITED STATES PATENT OFFICE

2,070,209

METHOD OF STORING AND BURNING
COMBUSTIBLE MIXTURESArthur N. Kerr, Los Angeles, Calif., assignor to
Phillips Petroleum Company, Bartlesville,
Okla., a corporation of Delaware

Application November 13, 1933, Serial No. 697,369

6 Claims. (Cl. 158—117.5)

This invention relates to improvements in heating systems employing as fuel relatively non-volatile hydrocarbon oil intimately mixed with liquefied hydrocarbon gases in such a way as to give a predetermined vapor pressure, and the present application is a continuation in part of my application Serial No. 637,797, filed October 14, 1932.

One of the objects of the invention is to mix the components of my improved mixture in a closed storage chamber or storage zone, and to employ both gaseous and liquid hydrocarbons in such proportions and in such a way that the mixture will remain in liquid condition until discharged at the burner. For this purpose, I preferably employ liquid hydrocarbons of the nature of kerosene in intimate admixture with liquefied petroleum gases of the nature of butane, propane or mixtures thereof.

Kerosene is an inexpensive fuel and is commonly burned in wick-type burners. It and heavier, less volatile oils are difficult to burn in generating burners, but are often utilized as fuel by forcing at high pressure through small orifices. I am aware that these heavy oils have been mixed with volatile oils in heating systems, but the mixing has been accomplished at or near the burner, and separate containers have been used for the separate liquids.

I have found that by adding to the oil a certain proportion of a liquefied combustible gas such as propane or butane, that the mixture is much more readily vaporized and burned. The average flash vaporization temperature of the mixture is much lower, the liquefied gas aiding materially in vaporizing the mixture in a generating device.

Another object of the invention is to provide a heating system in which a relatively non-volatile hydrocarbon oil of the nature of kerosene in intimate admixture with liquefied hydrocarbon gases of the nature of butane or propane may be stored in liquid condition in a storage zone, and may be fed in liquid condition through a restricted passageway to the zone of combustion, and wherein the heat resulting from burning of the mixture will raise the temperature of a generator forming part of the burner, so that the liquid hydrocarbons, as well as the normally gaseous hydrocarbons will readily burn within a very short time after the burner has been ignited.

An auxiliary object is to furnish such a system in which some of the hydrocarbon gases separated out of the hydrocarbon liquids may be employed directly to start the burner, and such

gas may be fed to the burner directly from the mixture storage tank. If it is desired, however, to maintain the mixture in the storage tank absolutely uniform, then the gas for ignition purposes may be fed to the burner from a smaller tank. In either event, the gas fed to the burner at the beginning will function to preheat the generating tube so that the liquid hydrocarbons, when subsequently fed to the burner in admixture with the liquefied gas, will be sufficiently heated in passing through the generating tube to readily vaporize.

Another object of the invention is to provide a liquid mixture of hydrocarbons containing enough dissolved gas so that when passed cold to the burner, it may be lighted and will burn, the unvaporized oil being led away to a reservoir until such time as the burner becomes sufficiently hot to vaporize the liquid hydrocarbons of the mixture.

A still further object is to supply a heating system of the above mentioned character, wherein gaseous hydrocarbons from the mixture tank may be fed to the burner through one tube, and the mixture be fed to the burner through a second tube, said tubes being associated with a thermostatically controlled valve, whereby after the burner is started with gas, the valve will function to cut off the flow of gas to the burner and to admit the flow of the mixture to the burner.

With the foregoing objects outlined and with other objects in view which will appear as the description proceeds, the invention consists in the novel features hereinafter described in detail, illustrated in the accompanying drawing, and more particularly pointed out in the appended claims.

In the drawing,

Fig. 1 is a diagrammatic elevation partly in vertical section of one form of a suitable apparatus for practicing my process.

Fig. 2 is a vertical sectional view through the thermostatically controlled valve.

Fig. 3 is a vertical sectional view of the burner.

With reference to the drawing, it will be noted in practicing my invention that I provide a pressure storage tank or storage zone 5, preferably buried beneath the ground and of a sufficient size to contain the desired amount of mixture. Arranged within the bottom portion of this tank 50 is a pipe 6 having perforations 7 for the purpose of bubbling liquefied hydrocarbon gases through relatively non-volatile combustible oil in the tank. Said gases are introduced into the pipe by means of a tube 8 which extends through a pressure-

tight joint 9 at the top of the tank, and has externally of the latter, a valve 10 and a part 11 of a pipe joint.

Another pipe 12 is connected to the top of the tank and terminates at its outer end portion in a valve 13 and a coupling member 14.

Into the tank, I introduce by way of pipe 12, a relatively non-volatile combustible oil of the nature of kerosene, and after the oil has been placed

10 in the tank, I introduce the liquefied hydrocarbon gas of the nature of propane or butane by means of pipes 3 and 6, and I prefer to use about 85% oil and about 15% gas. Obviously, these proportions, as well as the specific hydrocarbon

15 oils and gases may be varied, so long as the mixture may be fed through a tube in liquid condition and will ignite when exposed to flame.

A gas conducting pipe 15 has one of its ends connected to the top of the tank so as to lead 20 gas in gaseous condition from the latter, and the other end of this pipe terminates in an orifice member 16 which extends into the inlet of the mixing chamber of a burner 18 having outlet apertures 18a. Valves 19 and 20, interposed in

25 the pipe 15, when opened, permit gas to flow from the tank to the burner, and such gas may be ignited for the purpose of starting the burner.

For the purpose of feeding the mixture of normally gaseous hydrocarbons and normally liquid 30 hydrocarbons in liquid condition from the tank, two pipes 21 and 22 dip into the tank, and the outer end portions of these pipes are connected to a common feed pipe 24 by means of a cross pipe 23 in which valves 25 and 26 are interposed.

35 As one of the pipes, 21, dips into the tank deeper than the other pipe 22, this arrangement will enable the operator to determine when the liquid level of the mixture is getting low, and notify him of the necessity of recharging the tank.

40 Pipe 24 leads to the casing 37 of a thermostatically controlled valve 28, and the pipe has a valve 29 for controlling the flow of mixture through the pipe. When the valve 28 is opened, the mixture can flow through a tube 30 to the 45 inlet 31 of a burner control valve 32 which discharges into a generating tube 33 positioned in close proximity to the burner to be heated thereby. The heated mixture is discharged from the generating tube by means of a pipe 34 that leads 50 into the mixing chamber of the burner and terminates in an orifice member 35.

In order that the heat generated may be employed to control the valve 28, I extend a thermostatic rod 36 from the generating tube toward 55 the casing 37 of the valve 28, shown in detail in Fig. 2. This casing has a chamber 38 in which there is a valve seat 39 cooperating with a valve head 40 having a stem 41 that is moved in one direction by the expansion of the rod 36 to 60 allow the mixture to flow from the pipe 24 to the pipe 30. A portion 42 of the valve casing acts as a guide for the valve stem, and another portion 43 of the casing forms a chamber to house a coil spring 44 which acts to yieldingly 65 urge the valve head 40 towards its seat. Obviously, when the burner is not in operation, the rod 36 is contracted and the spring 44 holds the valve head against its seat and prevents the passage of the mixture through the pipe 24.

70 At this point it may be noted that if, for the purpose of ignition, gas is fed directly from the gas space in the top of the tank 5 through the pipe 15, this will tend to lower the pressure within the tank. Therefore, I draw liquid from the 75 line 24, through the valve 51, in the pipes 50 and

52 into tank 46. By closing valve 19 the gas which boils out of the liquid under reduced pressure may be used for starting the burner, passing through pipe 15 in the usual manner. After starting the burner thus, the liquid which gathers from the mixture in tank 46, can be discharged by way of pipe 53 having a valve 54, or it can be fed directly to pipe 52, 50, in which valve 51 is interposed.

In further reference to the auxiliary tank 46 it may be noted that it is difficult to start some burners with a mixture of the type which I employ, and burners, as a general proposition, have to be especially manufactured for my purposes. If I take an ordinary gasoline or kerosene burner of the generating type, it will not start to burn blue. Therefore, I employ the extra tank 46. This tank permits the withdrawal of some of the fuel from the main storage tank for the purpose of starting the burner without materially decreasing the pressure in the main tank. It is important that this pressure be maintained at about 30 pounds, and if propane was removed for starting, it might be used continuously, and thus the pressure in the main tank might be lowered to 10 pounds before the operator realized that the pressure had been reduced too low for operation of the system. By employing the auxiliary tank 46, some of the mixture may be run 25 into this tank for the purpose of removing enough propane to heat the generating tube of the burner. Once the generating tube is heated to say 700° F., all the kerosene ends are vaporized and the burner becomes in effect one which operates on propane, pure kerosene and propane gas. 30

Where proper mixtures of relatively non-volatile combustible oil, such as kerosene and liquefied combustible gases are used in proper ratios, such as about 85% oil to about 15% gas, this mixture may be ignited in the burner without preheating the latter by means of gas through pipe 15. Therefore, I can connect the pipe 24 anterior to the valve 29 to the pipe 30 by means of a pipe 59 which will lead from pipe 24 to a T-fitting 61 on the pipe 30. Valves 56 and 60 will be interposed respectively in the pipes 59 and 30, so that the thermostatic valve 28 may be by-passed to permit the liquid mixture to be fed directly from the storage tank to the orifice 35. 40

In starting the apparatus, in case some of the oil fails to vaporize and burn, it can be drained off from the burner through a pipe 56 into a tank 55.

From the foregoing it is believed the invention may be readily understood, and I am aware that changes may be made in the details disclosed, without departing from the spirit of the invention, as expressed in the claims. 55

What is claimed and desired to be secured by Letters Patent is:

1. In a method of the character described, 60 storing in a pressure chamber a relatively non-volatile combustible oil of the nature of kerosene in intimate admixture with a liquefied combustible hydrocarbon gas, feeding said mixture in liquid condition through a restricted passageway, 65 vaporizing the mixture and admixing it with a supporter of combustion, and then burning the final mixture.

2. In a method of the character described, 70 storing in a pressure chamber a relatively non-volatile combustible oil of the nature of kerosene in intimate admixture with a liquefied combustible gas of the nature of propane or butane, the oil being present in the mixture in larger per cent by weight than the gas, feeding the mixture

in liquid condition from said chamber under pressure set up by the regasification of said liquefied gas, through a restricted passageway, vaporizing the mixture and admixing it with a supporter of combustion, and then burning the final mixture.

5. In a method of the character described, storing in a pressure chamber a relatively non-volatile combustible oil of the nature of kerosene 10 in intimate admixture with a liquefied combustible gas of the nature of propane or butane, the oil forming at least 75% of said mixture by weight, feeding the mixture in liquid condition from said chamber under pressure set up by the 15 regasification of said liquefied gas, through a restricted passageway, vaporizing the mixture and admixing it with a supporter of combustion, burning the final mixture in a combustion space, and draining the unvaporized portion of said oil 20 from said space during the starting of the combustion operation.

4. A method of the character described, comprising storing a mixture of hydrocarbon oil and a liquefied normally gaseous hydrocarbon fluid 25 in a pressure container, feeding said mixture through a passageway, admixing a supporter of

combustion with said mixture, and burning the final mixture after it discharges from the outlet end of the passageway.

5. In a method of the character described, storing a mixture of normally liquid hydrocarbons and a liquefied normally gaseous hydrocarbon fluid, feeding said mixture in liquid condition from storage under the pressure set up by the regasification of said fluid, passing the mixture through a vaporizing chamber, admixing air 10 with said mixture and burning the final mixture after it leaves the vaporizing chamber.

6. In a method of the character described, storing in a pressure chamber a mixture of normally liquid hydrocarbons and a liquefied normally gaseous hydrocarbon fluid, the normally liquid hydrocarbons in the storage chamber constituting about 85% by weight of the mixture, feeding said mixture in liquid condition from the storage chamber under the pressure set up by 20 the regasification of said fluid, passing the mixture through a vaporizing chamber, admixing air with the mixture, and burning the final mixture after it leaves the vaporizing chamber.
